UNITED STATES PATENT OFFICE.

GEORGE F. HUTCHINS, OF WORCESTER, MASSACHUSETTS, ASSIGNOR TO CROMPTON & KNOWLES LOOM WORKS, A CORPORATION OF MASSACHUSETTS.

LOOM NEEDLE MECHANISM.

1,415,177.

Specification of Letters Patent. Patented May 9, 1922.

Application filed January 17, 1921. Serial No. 437,703.

To all whom it may concern:

Be it known that I, GEORGE F. HUTCHINS, a citizen of the United States, residing at Worcester, in the county of Worcester and 5 State of Massachusetts, have invented a new and useful Loom Needle Mechanism, of which the following is a specification.

This invention relates to needle mechanism for a loom in which two or more weft 10 threads are used, with picks of one kind interposed or alternating those of another.

It is the general object of my invention to provide a construction by which any selected needle may be operatively connected 15 to an actuating rod while the other needles remain inoperative.

With this general object in view, an important feature of my invention relates to the provision in a loom of a plurality of 20 relatively short needles or needle points, mounted in parallel relation and movable transversely to operative position relative to a regularly reciprocated needle actuating bar. A further feature of my invention relates to an improved connecting device by 25 means of which a selected needle may be detachably secured to the needle bar.

My invention further relates to arrangements and combinations of parts which will 30 be hereinafter described and more particularly pointed out in the appended claims.

A preferred form of my invention is shown in the drawings, in which

Fig. 1 is a front elevation of a portion of 35 a loom embodying my improvements;

Fig. 2 is a sectional side elevation taken along the line 2—2 in Fig. 1;

Fig. 3 is a plan view of the connecting device;

Fig. 4 is a front elevation, partly in section, of the parts shown in Fig. 3;

Fig. 5 is a horizontal sectional view taken along the line 5—5 in Fig. 2;

Fig. 6 is a sectional view showing the connection between the needle and the needle rod, and

Fig. 7 is a sectional detail elevation to be described.

Referring to the drawings, I have shown a 50 portion of the frame 10 of a loom of a usual type in which the weft threads are inserted in the warp by a positive needle motion.

A needle actuating rod 11 is secured in a

block 12 which is mounted to slide on guide-ways 13 (Fig. 2) fixed to the loom frame 10. 55 The block 12 has a pin and slot connection with a picker stick 14 mounted to swing about a fixed pivot 15, and given regular operative movements by actuating mechanism not shown.

The front end of the rod 11 has a bearing in a stand 16 which may be conveniently mounted on the support for the guide-way 13. Two or more short needles or needle points 17 are provided with headed rearward 65 extensions 19 (Fig. 6), which extensions are slidably supported in a transversely extend- ed slot 20 (Fig. 4) in the stand 16.

A notch 21 is provided in the rear end of each extension 19 and a plurality of plungers 70 22 are provided to yieldingly engage the needles in the notches 21, and thus prevent accidental displacement thereof. These plungers are mounted in the stand 16 and also in the rod 11. Springs 23 force the 75 plungers 22 yieldingly outward, such move- ment being limited by guide pins 24 in the plungers extending through slots 25 in the stand 16 or rod 11.

A cross slide 26 is mounted in the stand 16 80 above the slot 20, said slide being provided with downwardly and inwardly extending portions 27 (Fig. 2), adapted to enter the ends of the slot 20. A bell crank 28 is mounted on a fixed pivot 29 and has a pin 85 and slot connection with the slide 26.

The bell crank 28 may be connected by a link 30 to any suitable pattern-controlled ac- tuating mechanism by means of which the slide 26 will be moved transversely when- 90 ever a change of filling is desired. As the slide is thus moved transversely, one of the needles 17 will be moved out of alignment with the needle rod 11 and a different needle 17 will be moved into alignment therewith, 95 the needles being yieldingly retained in both old and new positions by the plungers 22 in the stand 16 and rod 11.

When the needle transfer is made, it is es- 100 sential that the rod 11 should be accurately positioned longitudinally in the stand 16. It is therefore desirable to provide a notch 31 (Fig. 7) in the rod 11 and to provide a spring pressed plunger 32 cooperating with the notch 31 to accurately position the needle 105 rod longitudinally.

Having thus described my invention, the operation and utility thereof is readily apparent.

Needles 17 are provided corresponding in number to the number of different kinds of weft which are to be used. These needles are yieldingly secured in parallel relation by inserting their headed rearward extensions 19 in the slot 20 of the stand 16, one of the needles being aligned with the needle rod 11. The needles are then shifted transversely by suitable pattern mechanism acting through the cross slide 26 so as to bring any selected needle into operative relation 15 with the needle rod.

After each movement of the cross slide 26, the needle rod is reciprocated to insert one or more picks of the selected weft in the warp.

20 While a preferred form of my invention has been shown and described, it will be evident that changes and modifications can be made therein by those skilled in the art within the spirit and scope of my invention 25 as set forth in the claims, and I do not wish to be otherwise limited to the details herein disclosed, but what I claim is:—

1. In a loom, a plurality of weft needles mounted for transverse movement, a reciprocating needle rod, means to move said needles relatively to said rod, and means to detachably secure a selected needle in alignment with said rod.

2. In a loom, a reciprocating needle rod, 35 a plurality of weft needles adjustably mounted for selective movement into co-operative relation with said rod, and means to move said needles transversely relatively to said rod to position a selected needle in 40 the path of said rod.

3. In a loom, a plurality of weft needles mounted for transverse movement, a needle rod and means to move and connect one needle with said rod and to simultaneously 45 remove and disconnect a second needle from said rod.

4. In a loom, a plurality of transversely movable weft needles, a reciprocating needle rod, means to move said needles to operative

and inoperative positions relative to said 50 rod, and means to hold said needles yieldingly in either position.

5. In a loom, a plurality of weft needles, 55 a stand in which said needles are mounted for transverse movement and are supported in parallel relation, means to yieldingly hold said needles in such relation, a needle rod movable toward and away from the fabric, and means to selectively move said needles and to connect a selected needle with 60 said rod when the latter is in its outward position.

6. In a loom, a stand, a plurality of weft needles mounted to slide transversely in 65 said stand, a needle rod mounted to reciprocate longitudinally in said stand, and means to move said needles transversely to connect and disconnect said needles from said rod.

7. In a loom, a reciprocating needle rod, 70 a plurality of weft needles adjustably mounted for selective movement into co-operative relation with said rod, means to move said needles to operative and inoperative positions relative to said rod, and means 75 to position said rod longitudinally during needle transfer.

8. In a loom, a plurality of weft needles having headed rearward extensions, a needle rod having an end slotted to receive 80 said extensions, a stand in which said needles are mounted for transverse movement relative to said rod and means to move a selected needle transversely to position its headed extension in the slotted end of 85 said needle rod.

9. In a loom, a stand, a plurality of weft needles yieldingly mounted to slide transversely in said stand, a needle rod mounted to reciprocate longitudinally in said stand, 90 and a cross slide mounted in said stand and effective to move said needles transversely to connect and disconnect said needles from said rod.

In testimony whereof I have hereunto 95 affixed my signature.

GEORGE F. HUTCHINS.
